United States Patent Office

Des. 211,454
Patented June 18, 1968

211,454

SAUNA BATH BUILDING

Leonard Hurst, Rexdale, Ontario, and George Dabrowski, Toronto, Ontario, Canada, assignors to J. A. Carasquel, Miami Beach, Fla.

Filed Aug. 7, 1967, Ser. No. 8,159

Claims priority, application Canada Feb. 14, 1967

Term of patent 7 years

(Cl. D13—1)

Fig 1

Fig 2

FIG. 1 is a perspective view of the design looking toward a front corner of the design; and

FIG. 2 is a rear view of the design looking toward the rear corner of the design opposite the front corner of FIG. 1.

The material shown in broken lines is for illustrative purposes only and does not form part of the design.

We claim:

The ornamental design for a sauna bath building, shown.
